UNDERWATER CAMERA HOUSING

Jack Birns, Sherman Oaks, Calif.

Application October 6, 1958, Serial No. 52,880

Term of patent 14 years

(Cl. D61—1)

Fig. 1.

Fig. 2.

Fig. 3.

Fig. 4.

Fig. 5.

Fig. 6.

Fig. 7.

Fig. 1 is a perspective view of an underwater camera housing showing my new design;

Fig. 2 is a front elevational view;

Fig. 3 is rear elevational view of the same;

Fig. 4 is a left side elevational view;

Fig. 5 is a right side elevational view;

Fig. 6 is a top plan view; and

Fig. 7 is a bottom plan view.

The dominant features of my design reside in the portions shown in full lines.

Portions of the drawing figures are diagonally lined to indicate transparency.

I claim:

The ornamental design for an underwater camera housing, as shown and described.
